UNITED STATES PATENT OFFICE

149,522

DESIGN FOR A GANTRY END FRAME

Ralph E. Smith and Lawrence H. Workman,
Muskegon, Mich., assignors to Manning, Maxwell & Moore, Inc., Muskegon, Mich., a corporation of New Jersey

Application July 13, 1946, Serial No. 131,559

Term of patent 14 years

(Cl. D54—1)

To all whom it may concern:

Be it known that we, Ralph E. Smith and Lawrence H. Workman, citizens of the United States, residing at Muskegon, in the county of Muskegon and State of Michigan, have invented a new, original, and ornamental Design for a Gantry End Frame, of which the following is a specification, reference being had to the accompanying drawing, forming part thereof.

Figure 1 is a perspective view of a gantry end frame embodying our new design.

Fig. 2 is a side elevational view of the frame.

Fig. 3 is a top view of the frame.

We claim:

The ornamental design for a gantry end frame, substantially as shown.

RALPH E. SMITH.
LAWRENCE H. WORKMAN.
